UNITED STATES PATENT OFFICE

168,015

TOY ANIMAL FIGURE OR THE LIKE

Arnold Henry Bergier, New York, N. Y., assignor to Flex-Art Inc., Rutherford, N. J., a corporation of New Jersey

Application March 29, 1951, Serial No. 14,662

Term of patent 3½ years

(Cl. D34—2)

To all whom it may concern:

Be it known that I, Arnold Henry Bergier, a citizen of the United States and resident of New York, in the county and State of New York, have invented a new, original, and ornamental Design for a Toy Animal Figure or the like, of which the following is a specification, reference being had to the accompanying drawing, forming a part thereof, and of which

Fig. 1 is a front perspective view of the toy animal figure, showing my new design, and

Fig. 2 is a rear perspective view thereof.

I claim:

The ornamental design for a toy animal figure or the like, as shown.
